(57) **CLAIM**

The ornamental design for a video borescope with attached stand as shown and described.

DESCRIPTION

FIG. 1 is an isometric view of a video borescope with attached stand showing our new design;

FIG. 2 is a back view thereof;

FIG. 3 is a right view thereof;

FIG. 4 is a left view thereof;

FIG. 5 is a top view thereof;

FIG. 6 is a bottom view thereof;

FIG. 7 is an isometric view thereof shown in an unfolded configuration;

FIG. 8 is a back view thereof shown in an unfolded configuration;

FIG. 9 is a right view thereof shown in an unfolded configuration;

FIG. 10 is a left view thereof shown in an unfolded configuration;

FIG. 11 is a top view thereof shown in an unfolded configuration; and,

FIG. 12 is a bottom view thereof shown in an unfolded configuration.

Elements shown in broken lines are for the purpose of illustrating portions of the video borescope with attached stand that form no part of the claimed design.

1 Claim, 12 Drawing Sheets
